UNITED STATES PATENT OFFICE.

KARL BÖHLE, OF ESSEN-ON-THE-RUHR, GERMANY, ASSIGNOR TO FRIED. KRUPP AKTIENGESELLSCHAFT, OF ESSEN-ON-THE-RUHR, GERMANY.

SWAGING PRESS.

Application filed December 3, 1920. Serial No. 428,115.

To all whom it may concern:

Be it known that I, KARL BÖHLE, residing at Essen-on-the-Ruhr, Germany, a citizen of the German Republic, have invented a certain new and useful Improvement in a Swaging Press, of which the following is a specification.

This invention relates to a swaging press for the manufacture of sheet metal end plates flanged outwards which will allow of producing in a single working operation end plates of the said kind in such wise that the flanged edge will obtain, either on its inner or else its outer face a shell surface which will possess practically speaking, an accurately rectilinear axial section.

Two embodiments of the subject matter of this invention are shown by way of example in the accompanying drawing, in which:

Figs. 1 to 3 are axial longitudinal sections of the essential parts of a swaging press of the customary kind,

Figs. 4 to 6 similar views of an improved swaging press subject to this invention,

Fig. 7 a like view of a modified form of construction.

In presses serving for the production of end plates flanged outwards, the sheet A (Fig. 1) which has been cut as required and may be heated to a red heat, is, as known, placed on the die B of the swaging press and forced down into said die by the action of the stamp C, whereby the flanged edge is formed. In the course of this operation the shell thickness of the said edge is increased from the bottom upwards towards its unsupported end; the increase in the shell thickness corresponding to the reduction which every diameter of a circle described on the edge concentrically to the longitudinal axis of the press before flanging, will be subject to during the swaging operation. For this reason, the width of the radial clearance intermediate stamp and die has, in the case of previous press structures, not been made to correspond to the original thickness f of the plate, but has been so selected as to be equal to at least the maximum thickness of plate f_1 occurring at the unsupported end of the flanged edge. By these means the possibility, is obviated of the sheet, at the unsupported end of the flanged edge, being pressed together again to its former thickness, whereby the further prog-

ress of the stamp would be to such an extent impeded as to cause such objectionable tensile stresses to arise that the sheet, as is frequently the case, will be liable to break in consequence. Now if the radial clearance existing between stamp and die be dimensioned in the manner indicated, then,

on the stamp being lowered, the sheet is primarily bulged in in the manner disclosed in Fig. 2. During the further course of the

pressing operation, the sheet tends to retain this bulged shape, the result being that on the conclusion of the pressing operation, there will arise, as Fig. 3 shows, a clearance intermediate the flanged edge—which fills

the radial clearance only at its unsupported end—and the shell surfaces of the two swaging tools, i. e. stamp and die. Hence, the flanged edge will neither obtain a cylindrical shape on its inner nor its outer face. Since,

however, in the case of end plates of this kind which are to be employed, say, as boiler ends, at least one of the shell surfaces appertaining to the outer flanged portion must be a cylindrical surface, it will consequently become necessary to shape one of said shell surfaces accordingly by means of an additional working operation.

It is the special feature of the swaging press in accordance with this invention by very simple means to obviate the necessity of carrying out this second, additional working operation.

In the form of execution shown in Figs. 4 to 6 that particular part of the stamp of the swaging press which is intended to be applied to the flanged edge comprises a cylindrical steel ring D so slotted in an oblique direction that the surfaces of separation d^1 and d^2 of the ring will, when not subject to any load spring apart for a certain distance α (Fig. 4). Again, that portion of the die destined to be brought in contact with the flanged edge consists of a rigid ring E. The dimensions of the two members D and E of the swaging press are so chosen, that the radius of the ring D of the empty stamp will be smaller for the extent of the plate thickness of the work F than the radius of the ring E of the die.

On the stamp being depressed, the work F is primarily bulged in in the manner shown in Fig. 2. In the further course of the pressing operation, the slotted ring D is now pressed together owing to the increase

of the plate thickness of the edge about to be flanged. At the same time, every section of the flanging edge coming in contact with the ring D, is forced against the internal 5 surface of the ring E of the die (Fig. 5) by reason of the spring action exerted by the compressed ring D. This will result in the outer shell surface of the flanged edge obtaining a cylindrical shape, without any subsequent machining being required. The force with which the flanged edge is pressed 10 against the shell surface of the ring E of the die may even be increased by making the clearance between the rings D and E 15 somewhat smaller than the thickness of the plate.

The second form of execution disclosed diagrammatically in Fig. 7, likewise relates to a swaging press for the manufacture of 20 sheet metal and plates, in the case of which it is intended that the internal shell surface of the flanged outer edge shall obtain a cylindrical form. In this case again that portion of the stamp destined to be brought 25 in contact with the flange in making comprises a rigid ring M, and the corresponding portion of the die of an obliquely slotted ring N of steel, the surfaces of separation n^1 and n^2 of which, the ring being subjected to no load, bear against each other.

The manner of operation differs from that of the form of construction shown in Figs. 4 to 6 only insofar as the slotted ring N of the die is bent apart by the fast of the 35 material of the work spreading out radially in the course of the pressing operation; it therefore calls for no further explanation. However, also in this case, there may be provided special auxiliary springs for the purpose of enhancing the elasticity of the slotted ring N. 40

Claims:

1. A flanging press for the manufacture of sheet metal plates flanged on their outer rim comprising a die having an annular flanging portion and a stamp having a flanging portion adapted to enter said flanging portion of the die in axial direction, one of said flanging portions being rigid and the other being adapted to elastically 45 yield transversely to said axial direction round its whole circumference in the sense of increasing the clearance left between it and the other flanging portion.

2. A flanging press for the manufacture 55 of sheet metal plates flanged on their outer rim comprising a die having an annular flanging portion and a stamp having a flanging portion adapted to enter said flanging portion of the die in axial direction, 60 one of said flanging portions being rigid and the other being a slotted ring adapted to elastically yield in the sense of increasing the clearance left between it and the other flanging portion.

3. A flanging press for the manufacture 65 of sheet metal plates flanged on their outer rim comprising a die having a rigid annular flanging portion and a stamp having a flanging portion adapted to enter said flanging portion of the die in axial direction, the flanging portion of the stamp being a slotted ring adapted to elastically yield in the sense of increasing the clearance left 70 between it and the other flanging portion. 75

The foregoing specification signed at Essen, Germany, this 23rd day of July, 1920.

KARL BÖHLE.

In presence of—
HANS GOTSMANN,
JOHANN DAECKERS.
